UNITED STATES PATENT OFFICE.

WARREN B. BUCKLEY, OF WASHINGTON, DISTRICT OF COLUMBIA.

DESIGN FOR A TIRE TREAD.

Application filed April 11, 1922. Serial No. 1,686. Term of patent 3½ years.

To all whom it may concern:

Be it known that I, WARREN B. BUCKLEY, a citizen of the United States, residing at Hotel Bellevue, Washington, District of Columbia, have invented a new, original, and ornamental Design for Tire Treads, of which the following is a specification, reference being had to the accompanying drawing, forming a part thereof, in which—

Figure 1 is a perspective view, and Figure 2 is a plan view of a portion of a tire tread, showing my new design.

I claim:

The ornamental design for a tire tread, as shown.

WARREN B. BUCKLEY.
